FOUNTAIN PEN

George Stewart Vivian, Norbury, London, England, assignor of one-half to T. B. Ford Limited, Buckinghamshire, England

Application November 13, 1931, Serial No. 574,826, and in Great Britain July 11, 1931

11 Claims. (Cl. 120—49)

This invention relates to improvements in fountain pens and comprises a method and means for effectively sealing the outlet from the reservoir of the pen so as to prevent leakage when not in use and which is automatically released when the pen is required for use.

The present invention broadly consists in the provision of means for isolating the reservoir of the pen from the ink outlet appropriate to the nib such means being automatically brought into 10 operation by the application of a removable cap to the pen.

The invention may be said to consist in that the pen and the pen cap are so constructed and arranged that the act of securing the pen cap in 15 position on the pen operates a closure valve to seal the outlet from the reservoir of the pen and so prevent the escape of ink therefrom. When the pen cap is removed to enable the pen to be used, the closure valve is automatically released 20 so that ink will flow from the reservoir to permit it to be used for writing immediately.

The closure valve is preferably located within the pen and is so arranged that by securing the pen cap in position for example by screwing it 25 upon a portion of the pen body relative movement is effected between the closure valve and the nib section or other part of the pen so as to cut off the supply of ink from the reservoir. The invention is applicable to reservoir fountain 30 pens both of the self-filling type and also of the type in which ink is introduced by means of a separate filling device. It is however, particularly applicable to reservoir fountain pens having pump actuated filling mechanism.

35 In a suitable method of carrying the invention into practice as applied to reservoir fountain pens having pump actuated filling mechanism, a valve may be located within the reservoir and supported near the outlet from the reservoir 40 to the nib section. The nib section and the valve are movable relatively to each other and this movement is effected by the act of securing the pen cap over the nib section. The pen cap is arranged to screw on to a portion of the body of 45 the pen while a sleeve within the pen cap engages against the nib section. As the pen cap is screwed into place the sleeve therein will press against the nib section causing relative movement between it and the closure valve until the 50 outlet is effectively sealed. When the pen cap is unscrewed and removed the converse movement will take place so as to unseal the outlet and permit ink to flow to the nib. Where necessary spring or other means may be employed to assist 55 this return movement.

The closure valve is preferably connected to or formed as a part of the plunger of the pump mechanism which when the pump is not in use for filling purposes will be located close to the ink outlet from the reservoir. When the pen cap is removed the closure valve will be released from the aperture to permit the flow of ink but when the pen cap is screwed into position the valve will seat in the outlet and effectively prevent the escape of ink. One method of effecting the relative movement between 60 the closure valve and the nib section consists in providing a sheath which fits over the pen body and may be screwed or otherwise connected to the head of the pump plunger. A spring or other means may be located within 65 the head of the pump plunger between it and the pen body so that the plunger is normally held in such a position that the closure valve at its end is free of the outlet through which ink flows from the reservoir to the pen nib. The 70 pen cap is adapted to be screwed on to the lower end of the outer sheath while a cylindrical or tubular projection from the head of the pen cap envelops the nib and engages against the end of the nib section. As the pen cap is screwed 75 into position on the outer sheath the tubular projection will press against the end of the nib section forcing it and the whole of the pen body to slide within the outer sheath against the action of the spring or other means. Thus the 80 nib section and the pen body will slide relatively to the pump plunger until the nib section is pressed against the closure valve thus sealing the outlet from the reservoir. When the 85 pen cap is removed the spring or other means 90 forces the pen body and the nib section away from the closure valve thus permitting ink to flow as required for writing purposes. The outer sheath may be easily detached and removed 95 from the pen body and reservoir when it is desired to fill the pen with ink. This is effected by inserting the end of the pen in the ink and operating the plunger so as to draw ink into the reservoir. When the pen has been filled 100 the outer sheath is again placed in position and the pen is ready for use. This obviates any possibility of ink getting on to the outside of the pen body or barrel.

In order that my invention may be clearly understood and readily carried into effect I have 105 appended hereto a sheet of drawings illustrating an embodiment thereof as applied to a self-filling fountain pen employing plunger mechanism somewhat similar to that described in co-pending application No. 449604, filed May 3, 1930, 110

Patent #1,862,586, issued June 14, 1932, and in which:-

Fig. 1 is a part sectional view of a complete pen.

5 Fig. 2 is a view showing the pen removed from its sheath.

Fig. 3 is a view illustrating the cap.

Fig. 4 is a sectional elevation of the sheath.

10 Fig. 5 is a broken sectional view of a complete pen, and

Fig. 6 shows the pen with the cap removed and ready for use.

Referring to the drawing the reservoir of the pen is a tubular body 1 which is preferably transparent and it has fitted into one end as a permanent fixture the nib receiving section 2 the nib being indicated by the reference numeral 3 and the quill which retains the nib in position being indicated by the reference numeral 4. The ink outflow passage is indicated at 5 and when the pen is in use the ink flows freely from the reservoir 1 through a valve seating 6 preferably of annular conical form as shown into this passage 5. When the pen is being charged with ink, the ink 20 is drawn through the passage 5 and air displaced by the ink issues through a lateral passage 7 at the lower end of an air vent passage 8 consisting of a small diameter tube extending axially along the reservoir and within a tubular piston rod 9 formed with an enlargement 10 of tubular form which on retraction of the piston rod is slidable through the piston 11 until a flange like abutment 12 thereon engages the piston 11 so that the piston is retracted to effect a suction or 30 charging action. The enlargement 10 is slotted longitudinally as at 13 to normally allow a free flow of ink, and if desired air, through the piston 11. The piston 11 is returned to its normal position by an annular abutment 14 of the enlargement 10 engaging the piston when the rod 9 is pushed home by means of its head 15.

The head 15 is fixed to the rod 9 and normally is threaded as at 16 into the upper end of a sheath 17 in which the reservoir fits as a close sliding fit. The other end of the sheath 17 is preferably tapered or coned as at 18 to conform with the normal configuration of a fountain pen and to receive the nib receiving section 2 which has at its free end a cylindrical part 19 slidable within but projecting from a correspondingly shaped free end 20 of the tapered part 18 of the sheath 17. This part 20 of the sheath has a threaded exterior 21 on which is adapted to be screwed a cap 22 and the arrangement is such that the action of screwing this cap 22 on to the threaded part 21 of the sheath isolates the ink outflow passage 5 from the reservoir by forcing a conically or otherwise suitably shaped valve 23 into the valve seating 6, this valve conveniently being carried by the lower end of the tubular piston rod 9 as shown.

The valve 23 is held off the seating 6 when the pen is in use by a coiled compression spring 24 accommodated in the piston rod head 15 which is bored centrally for this purpose as indicated at 25. This coiled compression spring is interposed between a gland nut 26 of a packing gland 27 through which the piston rod slides in the upper end of the reservoir 1 and the closed outer end 70 of the cap 15. When the safety cap 22 is screwed on to the threaded part 21 of the sheath 17 an abutment inside the cap 22 engages the annular free end of the cylindrical part 19 of the reservoir and forces the reservoir along the sheath 17 75 against the influence of the spring 24 until the

seating 6 is pressed against the valve 23. The abutment in the cap can be the annular free end of a sleeve 28 fitted into the safety cap 22 for example as shown by screwing it into the upper end of the cap for the purpose of gripping into position a pen clip 29. Alternatively the sleeve 28 can be integral with the cap 22.

It will of course be understood that the pen need not be a self-filling fountain pen as the rod 9 can be a small diameter rod merely fitted with the valve 23 and slidable through the gland 27 for a limited distance sufficient to enable the spring 24 to operate.

I claim:-

1. In a fountain pen, a reservoir, a nib connected with said reservoir, a sheath slidably accommodating said reservoir, a safety cap adapted to be applied over the nib, an ink outflow passage from the reservoir to the nib, a valve adapted upon application of said cap over the nib to automatically close said passage, a rod carrying said valve and slidable through the upper end of the reservoir, spring means operating on said rod to maintain the valve in the open position, a piston in said reservoir, abutments on said rod adapted to engage opposite sides of said piston for sliding the piston backwards and forwards in the reservoir to effect a filling operation, the nib receiving end of the reservoir projecting beyond the lower end of the said sheath and the said cap, 105 said safety cap being screwed on to the said sheath and being provided with an internal abutment adapted to engage the nib receiving end of the reservoir so as to effect said relative movement.

2. In a fountain pen, in combination, a sheath, a reservoir situated within said sheath and movable with respect thereto, a nib section connected with said reservoir at one end thereof, a valve seating formed in said end of the reservoir, a valve located inside said reservoir, a cover cap for covering said nib section, a thread formed on said sheath and adapted to receive said cap when said cap is applied over the nib section, and means for moving said reservoir relatively to said valve 115 and said sheath when said cover cap is applied over said nib section, said means drawing together said valve and said valve seating to isolate said reservoir from said nib.

3. In a fountain pen, in combination, a sheath, 125 a reservoir situated within said sheath and movable with respect thereto, a nib section connected with said reservoir at one end thereof and normally immovable relatively thereto, a valve seating formed in said end of the reservoir, a valve 130 located inside said reservoir, a cover cap for covering said nib section, a thread formed on said sheath and adapted to receive said cap when said cap is applied over the nib section, and means for moving said reservoir and said nib section as. 135 a single unit relatively to said valve and said sheath when said cover cap is applied over said nib section, said means drawing together said valve and said valve seating to isolate said reservoir from said nib.

4. In a fountain pen, a reservoir, a nib connected with said reservoir, a sheath over said reservoir, a safety cap adapted to be applied over said nib by being connected to one end of said sheath, means providing an ink outflow passage from said reservoir to said nib, a valve adapted upon application of said cap over said nib to automatically close said passage, a rod carrying said valve and slidable through the upper end of said reservoir, an operating member on the 150

- upper end of said sheath, said sheath operatively connecting said cap and operating member, and spring means operating on said rod to maintain said valve in the open position.
5. A fountain pen comprising a reservoir, a nib connected with said reservoir, a sheath accommodating the reservoir, an ink outflow passage connecting said nib to said reservoir, a valve adapted to close said passage, a cap adapted to be fitted over said sheath to enclose the nib, a rod carrying said valve and slidable through the upper end of the reservoir and connected to said sheath, and spring means operating on said rod to maintain the valve in the open position, such application of said cap being utilized to effect relative movement of said sheath and said valve with respect to said reservoir for the purpose of closing said passage.
6. In a fountain pen, a reservoir, a nib connected with said reservoir, a safety cap adapted to be applied over said nib, a sheath applied over said reservoir and adapted to be connected with said safety cap, an ink outflow passage from the reservoir to the nib, a valve adapted upon application of said cap over the nib to automatically close said passage, a rod carrying said valve and slidable through the upper end of the reservoir, resilient means operating on said rod to maintain the valve in the open position, and a rod cap connected to the outer end of said rod and to the corresponding end of said sheath and slidable over the corresponding end of the reservoir, said rod cap accommodating said spring means.
35. 7. A fountain pen comprising a reservoir, a nib connected with said reservoir, a sheath accommodating said reservoir, an ink outflow passage connecting said nib to said reservoir, a valve adapted to close said passage, a cap adapted to be fitted over said sheath to enclose said nib, a rod carrying said valve and slidable through the upper end of said reservoir, said rod being connected to said sheath, spring means operating on said rod to maintain the valve in the open position, and another cap fixed to the outer end of said rod and slidable over the corresponding end of the reservoir, the last-mentioned cap accommodating said spring means, the application of said cap to said sheath being utilized to effect relative movement of said sheath and said valve with respect to said reservoir for the purpose of closing said passage.
8. In a fountain pen, a reservoir, a nib connected with said reservoir, a safety cap adapted to be applied over said nib, a sheath adapted to be connected to said safety cap and surrounding said reservoir, an ink outflow passage from the reservoir to said nib, a valve adapted upon application of said cap over said nib to automatically close said passage, a rod carrying said valve and slidable through the upper end of the reservoir, said rod being connected to said sheath, spring means operating on said rod to maintain the valve in the open position, and another cap fixed to the outer end of said rod and slidable over the corresponding end of the reservoir, the last-mentioned cap accommodating said spring means, the application of said cap to said sheath being utilized to effect relative movement of said sheath and said valve with respect to said reservoir for the purpose of closing said passage.
55. 9. A fountain pen comprising a reservoir, a nib connected with said reservoir, a sheath slidably accommodating said reservoir, an ink outflow passage connecting said nib to said reservoir, a valve adapted to close said passage, a cap adapted to be fitted over said sheath to enclose said nib, such application of said cap being utilized to effect relative movement of said reservoir in the sheath relative to said valve for the purpose of closing said passage, the nib receiving end of the reservoir projecting beyond the lower end of the said sheath and the said cap, said safety cap being screwed onto the said sheath and comprising an internal abutment adapted to engage the nib receiving end of the reservoir so as to effect said relative movement, and spring means adapted to maintain said valve open and opposing said relative movement.
10. In a fountain pen, in combination, a reservoir, a nib section connected with said reservoir at one end thereof, a valve seating formed in said end of the reservoir, a valve located inside said reservoir, a cover cap for covering said nib section, a member extending along the exterior of the reservoir and forming a mechanical connection from said cap to said valve, and means moving said reservoir relatively to said valve when said cover cap is applied over said nib section, said means drawing together said valve and said valve seating to isolate said reservoir from said nib.
11. In a fountain pen, in combination, a reservoir, a nib section connected with said reservoir at one end thereof and normally immovable relatively thereto, a valve seating formed in said end of the reservoir, a valve located inside said reservoir, a cover cap for covering said nib section, a member extending along the exterior of said reservoir and forming a mechanical connection from said cap to said valve, and means moving said reservoir and said nib section as a single unit relatively to said valve when said cover cap is applied over said nib section, said means drawing together said valve and said valve seating to isolate said reservoir from said nib.
